(57) **ABSTRACT**

A toothbrush that enhances cleaning and user comfort while brushing. In one embodiment, the toothbrush comprises a cleaning element support member, or base member, that permits a head of the toothbrush to be comfortably received and manipulated within the user's mouth. In an embodiment, the support member comprises a head support having an overhanging portion and a portion free of an overhang.

**CROSS-REFERENCE TO RELATED PATENT
APPLICATIONS**

The present application is a continuation-in-part of U.S. patent application Ser. No. 12/576,445, filed Oct. 9, 2009, which in turn is a continuation-in-part of U.S. patent application Ser. No. 11/053,589, filed Feb. 8, 2005, now U.S. Pat. No. 7,725,981, which in turn is a continuation of Patent Cooperation Treaty Patent Application Serial No. PCT/US2003/024879, filed Aug. 8, 2003, which in turn claims the benefit of U.S. Provisional Patent Application Ser. No. 60/402,165, filed Aug. 9, 2002.

The Present application is also a continuation-in-part of U.S. patent application Ser. No. 11/535,259, filed Sep. 26, 2006, which in turn claims the benefit of U.S. Provisional Patent Application Ser. No. 60/720,418, filed Sep. 26, 2005.

The entireties of the above-referenced patent applications are hereby incorporated by reference.

FIELD OF THE INVENTION

The present invention relates to toothbrushes.

BACKGROUND OF THE INVENTION

Conventional toothbrushes usually include a substantially rigid head with an outer surface from which cleaning elements extend. Conventional cleaning elements include bristles arranged in bristle tufts, elastomeric members or other known cleaning elements. However, rigid portions of certain conventional toothbrush heads can prevent the cleaning elements from being comfortably received in the mouth, and thereby prevent effective cleaning of the oral cavity.

To eliminate the problems associated with large, rigid toothbrush heads, certain conventional toothbrush heads include flexible segments that allow carried cleaning elements to move relative to the head. However, these flexible segments may not fit comfortably within the mouth of the user. Similarly, because of the size and/or shape of the flexible segments, the heads may not be comfortably manipulated within the mouth of the user during cleaning. As a result, the toothbrush may not be used on a regular basis. Additionally, when introduced into the mouth, the toothbrush may not be used for a period of time sufficient to provide the person with effective oral cleaning. It is also possible that the cleaning elements may not be capable of reaching all intended portions of the mouth. This can result in poor oral hygiene that can cause tooth and/or gum disease.

A number of approaches have been taken in the prior art to provide flexibility to the bristles during use of a toothbrush. U.S. Pat. No. 5,970,564, for example, discloses a toothbrush having an elastomeric ridge wherein there is a center array of bristles and there is a side array of bristles mounted in elastomeric boots. A number of patents disclose a toothbrush head having sets of bristles, each of which is mounted to a non-rigid or elastic support element. Examples of these approaches are found in U.S. Pat. Nos. 1,770,195, 2,244,098, 6,161,245 and 6,311,360 and in French Patent No. 38440.

BRIEF SUMMARY OF THE INVENTION

In one embodiment, the invention can be a toothbrush comprising: a head extending along a longitudinal axis from a first end proximate a neck to a second free end distal the neck, the head comprising a base: a cleaning element support

2

member comprising a stem extending from the base and a support head, the stem comprising a first portion and a second portion, the support head having an outer peripheral edge comprising a first portion that overhangs the second portion of the stem and a second portion that is free of an overhang relative to the first portion of the stem; the first portion of the stem, the second portion of the outer peripheral edge of the support head, and a portion of an outer surface of the base forming a continuous surface at the second free end of the head; a gap formed between an undersurface of the support head and the base, the support head having an overhanging portion capable of deflecting into the gap in the direction of said base; tooth cleaning elements extending from the support head of the cleaning element support member; the support head having a greater width than the stem; the continuous surface at the second free end of the head comprising a convex curve; the overhanging portion of the support head extending from the stem in a cantilevered manner toward the first end of the head; the overhanging portion extending a first distance from the stem and the undersurface of the support head separated from the base by a second distance via the gap, the first distance being greater than the second distance; the tooth cleaning elements positioned on the support head so that: (1) a first axis that is substantially normal to said longitudinal axis of said head intersects said gap and a point on a top surface of the support head from which at least one of said tooth cleaning elements extends; and (2) a second axis that is substantially normal to said longitudinal axis of said head intersects said stem and a point on a top surface of the support head from which at least one of said tooth cleaning elements extends; and the stem located on the longitudinal axis.

In another embodiment, the invention can be a toothbrush comprising: a head extending along a longitudinal axis from a first end proximate a neck to a second free end distal the neck, the head comprising a base: a cleaning element support member comprising a stem extending from the base and a support head, the stem comprising a first portion and a second portion, the support head having an outer peripheral edge comprising a first portion that overhangs the second portion of the stem and a second portion that is free of an overhang relative to the first portion of the stem; the first portion of the stem, the second portion of the outer peripheral edge of the support head, and a portion of an outer surface of the base forming a continuous surface at the second free end of the head; a gap formed between an undersurface of the support head and the base, the support head having an overhanging portion capable of deflecting into the gap in the direction of said base; and tooth cleaning elements extending from the support head of the cleaning element support member.

In yet another embodiment, the invention can be a toothbrush comprising: a head extending along a longitudinal axis from a proximal end to a free distal end, the head comprising a base; a cleaning element support member extending from the base and comprising a stem located on the longitudinal axis and a support head having an outer peripheral edge, the stem comprising a first portion and a second portion, a first portion of the outer peripheral edge of the support head overhanging the second portion of the stem and a second portion of the outer peripheral edge of the support head free of an overhang relative to the first portion of the stem; the first portion of the stem, the second portion of the outer peripheral edge of the support head, and a portion of an outer surface of the base forming a continuous surface at the free distal end of the head; and tooth cleaning elements extending from the support head of the cleaning element support member.

In still another embodiment, the invention can be a toothbrush comprising: a head extending along a longitudinal axis from a proximal end to a free distal end, the head comprising a base; a cleaning element support member extending from the base and comprising a support head, the support head comprising an outer peripheral edge and an overhanging portion; a portion of the outer peripheral edge of the support head and a portion of an outer surface of the base forming a continuous surface at the free distal end of the head; a gap formed between an undersurface of the overhanging portion of the support head and the base, the overhanging portion capable of deflecting into the gap in the direction of said base; and tooth cleaning elements extending from the support head of the cleaning element support member.

In a further embodiment, the invention can be a toothbrush comprising: a handle; a head connected to said handle and extending along a longitudinal axis from a proximal end to a distal end, the head having: a body portion; a base member at a distal end of the head protruding outwardly from a front surface of the body portion, the base member being substantially non-movable relative to the body portion and comprising at least one outwardly extending tooth cleaning element; a plurality of pods, each of the plurality of pods comprising at least one outwardly extending cleaning element, each of the plurality of pods movable relative to the body portion and resilient so that the at least one cleaning element of said plurality of pods is movable from an initial position and being returnable to said initial position; and a channel separating adjacent ones of the plurality of pods so that each of the plurality of pods can move independent of one another.

Further areas of applicability of the present invention will become apparent from the detailed description provided hereinafter. It should be understood that the detailed description and specific examples, while indicating the preferred embodiment of the invention, are intended for purposes of illustration only and are not intended to limit the scope of the invention.

BRIEF DESCRIPTION OF THE DRAWINGS

The present invention will become more fully understood from the detailed description and the accompanying drawings, wherein:

FIG. 1 is a perspective view of a toothbrush in accordance with this invention;

FIG. 2 is a side elevational view of the toothbrush shown in FIG. 1;

FIG. 3 is a front elevational view of the toothbrush shown in FIGS. 1-2;

FIG. 4 is a side elevational view similar to FIG. 2 partially broken away;

FIG. 5 is a side elevational view showing a subassembly of the bristle containing portion of the brush head in accordance with another aspect of this invention;

FIG. 6 is a side elevational view showing the subassembly of FIG. 5 incorporated in a completed toothbrush; and

FIG. 7 is a front elevational view of a further toothbrush in accordance with this invention.

FIG. 8 is a top view of a portion of a toothbrush in accordance with an aspect of the present invention;

FIG. 9 is a cross section of an exemplary cleaning element support member according to an aspect of the present invention;

FIG. 10 is a cross section taken along line 3-3 of FIG. 8;

FIG. 11 is an end view of the portion of the toothbrush shown in FIG. 8; and

FIG. 12 is an elevational view of a portion of the toothbrush shown in FIG. 8 taken opposite the view of FIG. 11.

DETAILED DESCRIPTION OF THE INVENTION

The following description of the preferred embodiment(s) is merely exemplary in nature and is in no way intended to limit the invention, its application, or uses.

FIGS. 1-4 illustrate a toothbrush 10 in accordance with one aspect of this invention. As shown therein toothbrush 10 includes an elongated hand-held handle 12 with a head 14 connected to and extending from the handle. The head 14 is divided into a plurality of separate cleaning areas which are spaced from each other. As illustrated the cleaning areas include a base member 16 located at the distal end of the head 14 and projecting outwardly from the main body portion 30 (which can also be considered a base 30) of the head. Base member 16 includes at least one and preferably a plurality of cleaning elements 18. Head 14 further includes a base member or supporting member 20 at the proximal end of head 14. Cleaning elements 18 also extend outwardly from base member 20.

Mounted between the cleaning areas which incorporate base members 16 and 20 are a pair of pods 22, 24. Each pod is provided with at least one and preferably a plurality of cleaning elements 26. As later described the pods 22, 24 have a greater degree of movability than do the base members 16, 20. In the preferred practice of the invention the pods 22, 24 are resilient members so that the pod cleaning elements add a motion range beyond the cleaning elements 18 which are generally static or non-movable. Preferably, because the various cleaning elements are separated from each other such as by channels 28 which extend completely across head 14 in a transverse direction and because of the elastic nature of pods 22, 24, the cleaning elements 26 are capable of 360 degrees rotation about the vertical axis of each individual pod. The angle of the bend is dictated by the ability of the material to bend.

Toothbrush 10 thus provides a head 14 wherein the front (distal end) and the back (proximal end) areas are in a relatively fixed position and wherein the cleaning elements, such as bristle strands, 18 do not have any extra degree of motion. The middle portion of head 14, however, has two areas of cleaning elements 26, 26 which are capable of 360 degree rotation.

As best shown in FIG. 4 the head 14 includes a main body portion/base 30 which supports the base members and pods. Body portion/base 30 and base members 16 and 20 are preferably made from conventional hard plastic materials, such as polypropylene, commonly used in the making of toothbrush handles and heads. Pods 22, 24, however, are made so as to be resilient. In the preferred practice of this invention, the resiliency of pods 22, 24 is achieved by providing a thin diameter beam 32 which extends from the main body portion/base 30 of the head of the toothbrush. Beam 32 is joined into the bottom of a thin pad or plate 34 which provides a support area onto which the cleaning elements 26 are affixed. The manner of mounting the cleaning elements 26 to the support pads 34 can be achieved utilizing various cleaning elements, such as bristles and other cleaning materials, in known attachment methods.

The desired flexibility or resiliency of the pods 22, 24 is enhanced by enclosing the thin beams 32 in elastic material 36 which could be acquired during the multi-injection molding process. The elastic material 36 serves as a rubber band by returning the beams 32 to their original form or initial position. This return action creates an active motion in the oppo-

site direction of the beam bend which aids in the cleaning of teeth by introducing extra brushing strokes.

As best shown in FIGS. 1, 2 and 4 the pods 22, 24 include a widened portion disposed toward the body/base 30. The support pads 34 are also widened. Each pod has a narrow or reduced diameter central portion 38 longitudinally intermediate the length of each pod. Thus, each pod is of generally mushroom shape.

Beam 32 could be of any suitable shape such as having a cross-section which is circular, square or any other geometric shape that provides a thin dimension or thin diameter to the beam to facilitate the bendability of the beam. The elastomer 36 may be considered as a continuous layer of any suitable thickness which covers the entire central area of head 14 as illustrated so that both pods 22, 24 are incorporated as part of the same elastic material. The portion of the head 14 which includes pods 22, 24 may be formed as a separate subassembly similar to the subassembly later described with respect to FIG. 5-6.

Although the invention could be practiced with a single base and a single pod and could be practiced with the base member having some, but a lesser degree of flexibility than the pod, the invention is preferably practiced wherein the base member is generally static or non-movable. In addition, the invention is preferably practiced where there are a plurality of such base members and a plurality of pods. The drawings illustrate a preferred practice of the invention where there are a total of four separate cleaning areas with the pods being located in the central portion of head 14. The invention is also preferably practiced where the cleaning elements comprise a plurality of bristles or strands on each base member and each pod.

As illustrated in FIG. 3 each base member 16 and 20 and each pod 22 and 24 has a generally oval outer surface. The base members and pods are longitudinally aligned, but spaced from each other by the depressions or open areas which form the channels 28. As also illustrated in FIG. 3 the pods have a larger outer surface or cleaning element carrying surface than do the base members.

As shown in FIG. 2 the terminal surfaces of the cleaning elements 18 and 26 are tapered so that the terminal surfaces of the cleaning elements 18 taper outwardly in a direction toward the center of head 14 while the terminal surfaces of cleaning elements 26 taper outwardly in a direction away from the center of head 14. Thus, the highest points of each set of cleaning elements 18 and its adjacent set of cleaning elements 26 are generally disposed toward each other for each pair of base member and pod 16, 22 and 20, 24.

Any suitable form of cleaning elements may be used as the cleaning elements 18 and 26 in the broad practice of this invention. The term "cleaning elements" is intended to be used in a generic sense which could include conventional fiber bristles or massage elements or other forms of cleaning elements such as elastomeric fingers or walls arranged in a circular cross-sectional shape or any type of desired shape including straight portions or sinusoidal portions. Where bristles are used, the bristles could be mounted to tuft blocks or sections by extending through suitable openings in the tuft blocks so that the base of the bristles is mounted within or below the tuft block.

Using different cleaning materials as cleaning elements of the toothbrushes may yield different effects. In an attempt to provide better stain removal a rubber-like material or elastomer can be used in combination with conventional bristles or used by itself to "brighten/whiten" the teeth.

It is to be understood that the specific illustration of the cleaning elements is merely for exemplary purposes. The

invention can be practiced with various combinations of the same or different cleaning element configurations (such as stapled or in-molded technology bristles, etc.) and/or with the same bristle or cleaning element materials (such as nylon bristles, spiral bristles, rubber bristles, etc.) Similarly, while FIG. 2 illustrates the cleaning elements to be generally perpendicular to the outer surface of head 14, some or all of the cleaning elements may be angled at various angles with respect to the outer surface of head 14. It is thereby possible to select the combination of cleaning element configurations, materials and orientations to achieve specific intended results to deliver additional oral health benefits, like enhanced cleaning tooth polishing, tooth whitening and/or massaging of the gums.

FIGS. 5-6 illustrate a further aspect of this invention relating to techniques for forming the toothbrush. The toothbrush 10A has the ability to provide flexible support for the bristles 26A in designated areas. The flexibility is provided by designing the tuft holding areas 34A as plates which in combination with the stems 38A forms pods of mushroom shape. The mushroom stem 38A is made flexible to allow the plate 34A populated with bristles or cleaning elements 26A to move in different directions while brushing, as described with respect to the flexible pods of FIGS. 1-4.

FIGS. 5-6 show the toothbrush 10A and in particular the cleaning element or bristle carrying portion 23 of the head 14A to be made utilizing an IMT process. As shown in FIG. 5 the bristle or cleaning element carrying portion 23 forms an initial subassembly. This subassembly is made by introducing the cleaning elements 26A into the mold cavity into which a plastic material is injected. As the material injected cools off it permanently traps the bristles or cleaning elements 26A to form a brush or subassembly 23.

To achieve a functional flexibility and proper tuft retention 35 the portion of the bristle holding part or subassembly 23 which comprises the plates 34A, stems 38A and interconnecting support 25 is preferably a blend of polypropylene (PP) and soft TPE. Once the PP/TPE blend is combined with the bristles 26A the subassembly 23 is formed. In an initial independent IMT step the subassembly 23 is then overmolded 40 with an entire toothbrush handle 12A and head 14A during a second injection cycle to form the completed toothbrush 10A shown in FIG. 6. If desired or required the entire handle 12A and head 14A absent the subassembly 23 could be made first and the subassembly or bristle retaining portion 23 made second.

Other IMT toothbrushes that have bristles attached to the bulk of the handle as known in the prior art are difficult to make because of the slow injection speed needed to fill the head of the toothbrush. The present invention permits the making of an entire handle at normal speeds by isolating the IMT process for making subassembly 23 to the smaller material shot size. Although a blend of PP/TPE is a preferred practice of this invention such blend is not required to make 55 an IMT brush using the method of this invention. Similarly, the invention may be practiced using compatible materials to fuse the first and second shots so that the subassembly 23 created in one of the shots will be secured to the remainder of the toothbrush in the other shot. Thus, the two shots are 60 mechanically trapped together to achieve essentially the same benefits as achieved by combining the subassembly 23 with the remainder of the toothbrush in a second injection cycle.

It is to be understood that the invention described in FIGS. 5-6 could be practiced where all portions of the head 14 include the flexible mushroom sections without having less flexible base portions such as base members 16 and 20 of FIGS. 1-4. Similarly, the subassembly two shot techniques of

FIGS. 5-6 could be utilized in the embodiment of FIGS. 1-4 for forming the two or more central pods 22, 24 as a single subassembly initially made separate from the remainder of the toothbrush head 14. The final toothbrush would be made in a second injection molding process wherein the subassembly having interconnected pods 22, 24 would be molded to the handle 12 and head 14 made of more rigid material.

As noted, FIG. 2 illustrates the terminal surfaces of the cleaning elements 18 and 26 to be tapered in an up and down or zig zag manner. FIGS. 5-6 show an alternative taper wherein the terminal surfaces form a smooth, gentle, concave shape. If desired, other shapes may be used such as a planar shape for the terminal surfaces or a convex shape as well as the zig zag or up and down shape shown in FIG. 2. Similarly, the terminal ends of the cleaning elements in the FIGS. 1-4 embodiment, as well as those of FIGS. 5-6, could have the various shapes such as zig-zag, convex, concave or planar.

Although FIGS. 1-4 and 5-6 illustrate a manually operated toothbrush, the invention may also be practiced where the head includes one or more power or electrically operated movable sections carrying cleaning elements. Such movable section may oscillate in a rotational manner or may oscillate linearly in a longitudinal direction with respect to the longitudinal axis of the head or may oscillate linearly in a lateral or transverse direction with respect to the longitudinal axis of the head. The movable section may oscillate in and out in a direction toward and away from the outer surface of the head. The movable section may rock back and forth with respect to the outer surface of the head. The movable section may rotate continuously in the same direction, rather than oscillate. Any suitable drive mechanism may be used for imparting the desired motion to the movable section. Where plural movable sections are used, all of the movable sections may have the same type and direction of movement, or combinations of different movements may be used.

FIG. 7 illustrates a toothbrush 10B which includes a power driven movable disc or section 40 having cleaning elements. The movable section 40 could be oscillated rotationally such as by using the type of drive mechanism shown in U.S. Pat. No. 5,625,916, or could move in and out using the type of drive mechanism shown in U.S. Pat. No. Re. 35,941, all of the details of both patents are incorporated herein by reference thereto. Alternatively, the other types of drives referred to above could move section 40 in other manners and directions. Although FIG. 7 shows movable section 40 to be at the distal end of the head, the movable section(s) could be located at any desired location on the head.

FIG. 8 illustrates a toothbrush 510 according to an aspect of the present invention. The toothbrush 510 includes an elongated handle (not shown) that may be formed of any shape and with a variety of constructions that permit the toothbrush 510 to be readily gripped and manipulated for effective tooth and gum cleaning. The toothbrush 510 also includes a neck 514 and a head 520 having a first end 521 proximate the neck 514 and a second, free end 22 distal the neck 514. The head 520 also includes a base 524 and spaced cleaning element support members 526. The base 524 provides an area onto which the cleaning element support members 526 are secured, in any known manner (See FIG. 9).

FIG. 9 illustrates an isolated example of a cleaning element support member 526 according to an aspect of the present invention. The exemplary cleaning element support member 526 includes a stem 527 and a flexion control member 528 positioned within the stem 527. The cleaning element support members 526 also include a support head 523 with a section 529 that overhangs the stem 527 in the direction of the center of the other cleaning element support members 526. The body

of the stem 527 that surrounds each flexion control member 528 and each support head 523 are formed of flexible materials, such as flexible resins. In an embodiment, the flexible resins usable with the support members 526 include soft thermoplastic elastomers (TPE). Other soft, resilient materials can also be used to form the stems 527 and the support heads 523. The resilient material of the support members 526 serves to bias the stems 527 and flexion control members 528 back to initial, rest position after they have been deflected.

10 This return action creates an active motion in the opposite direction of the initial flexion of the support members 527, which aids in the cleaning of teeth by introducing additional cleaning strokes and by strengthening the cleaning stroke because of the bias force created by the material.

15 The flexion control members 528 limit the flexibility of their respective support members 526. The internally extending flexion control members 528 can be of any shape that allows some flex and have a cross-section that is circular, square or any other geometric shape that provides a thin dimension or thin diameter about which the support member 526 can bend. The size of this thin dimension/diameter can contribute to the total amount of flex experienced by each cleaning element support member 526.

20 The flexion control members 528 are each secured to the base 524 or alternatively they are formed together with the base 524 as an integral unit. The flexion control members 528 can be formed of conventional hard plastic materials, such as polypropylene. In an alternative embodiment, the flexion control members 528 can be formed of a more flexible material that allows their respective stems 527 additional movement in a direction at an angle to its length during brushing. For example, each stem 527 would be capable of deflecting in a direction toward the center of the head 520 and, in embodiments, for example, with circular cross sections, deflect in all 25 directions that extend at an angle to the longitudinal axis of the support member 526.

25 The cleaning element support members 526 also include carriers 525 that each supports at least one cleaning element 550. The cleaning elements can be used to clean the teeth, gums and/or tongue of a user. In the illustrated embodiment of FIG. 8, the cleaning elements 550 are in the form of bristles arranged in bristle tufts 552 that are secured to the carriers 525. However, one or more elastomeric members or other forms of cleaning members may be used to form the cleaning elements in lieu of or in addition to the use of bristles arranged in bristle tufts. The term "cleaning element" is intended to be used in a generic sense which could also include massage elements and other forms of cleaning elements such as elastomeric fingers or walls arranged in a circular cross-sectional shape or any type of desired shape and/or cross-section including straight portions or sinusoidal portions.

30 The carriers 525 are each supported by a flexion control member 528 and secured to the support head 523 of their respective stem 527, as illustrated in FIG. 9. The carriers 525 are preferably formed from conventional hard plastic materials, such as polypropylene, commonly used in the making of toothbrush handles and heads. However, other known hard materials can be also be used. The cleaning elements 550 extend from the carriers 525 for performing an oral care function within the mouth of the user. The tooth cleaning elements 550 can be anchored to their carrier 525 using any known technique. For example, the tooth cleaning elements 550 can be anchored into their carrier 525 during the formation of the carrier 525 (e.g., in mold tufting or anchor free tufting). Alternatively, the cleaning elements 550 can be anchored using other known techniques, such as, stapling, pinning or gluing.

While FIGS. 9-12 illustrate the cleaning elements 550 oriented generally perpendicular to the outer surface of base 524, some or all of the cleaning elements 550 may be oriented at various angles with respect to the outer surface of the base 524. It is thereby possible to select the combination of cleaning element configurations, materials and orientations to achieve specific intended results to deliver additional oral health benefits, like enhanced cleaning, tooth polishing, tooth whitening and/or massaging of the gums.

As shown in FIGS. 8-10, the head 520 includes a plurality of the exemplary cleaning element support members 526. In the illustrated embodiment, the head 520 includes three spaced cleaning element support members 530, 540, 560 having the same components as support members 526. However, the head 520 can include only two or more than three support elements spaced along the head 520. The positioning of the support elements 526 along the head 520 is not limited to the linear arrangement illustrated in the figures. Instead, the support elements 526 can be arranged in any fashion on the head 520.

As illustrated in FIG. 10, the first support member 530 is positioned at the first end 521 of the head 520. The body of this support member 530 includes a stem 532 and a support head 533. The stem 532 forms a smooth, continuous surface 516 with a portion 517 of the head 520 proximate the neck 514. The continuous surface 516 formed between the head 520 and the stem 532 is sized and shaped so it will be easily received and manipulated within the mouth. The continuous surface 516 provides a profile having a shape that is similar to that of a comfortable, conventional toothbrush head. Additionally, the soft material used to form the stem 532 will deflect when it engages a portion of the user's mouth. As a result, the soft, flexible material of the stem 532 provides the user with additional comfort.

The support head 533 has a greater diameter/width than the stem 532 that extends away from it toward the neck 514. The portion 535 of the support head 533 that overhangs the stem 532 creates a partial mushroom-shaped profile. This portion 535 is also movable relative to the stem 532 and the base 524, as illustrated by the arrows in FIG. 10. The overhanging portion 535 has a lower surface 536 spaced from the base 524 by a distance 538. As shown, a channel 539 is formed between the lower surface 536 and the base 524. The distance 538 is greater than the distance 537 that the overhanging portion 535 extends beyond the stem 532 in the direction of the second end 522. The distance 538 allows the overhanging portion 535 to deflect toward the base 524.

The flexion control member 531 within the stem 532 limits the total deflection of the support member 530 and cooperates with the material of the stem to return the stem 532 and its carrier 525 to their original, rest position. This deflection and return movement of the stem 532 and its carrier 525 allow the cleaning elements 550 to follow the teeth during cleaning and create an enhanced cleaning action within the mouth of the user. In an alternative embodiment, the distance 538 could be shorter than the distance 537. In such an embodiment, the base 524 could limit the travel of the overhanging portion 535. Regardless of the distance 538, the support member 530 is capable of achieving 360 degrees of movement relative to its central longitudinal axis.

The second end 522 of the head 520 also includes the second cleaning element support member 540 that forms a continuous smooth surface 541 with the free end of the base 524 at the second end 522 of the toothbrush 510. The continuous surface 541 is sized and shaped so it will be easily received and manipulated within the mouth of the user. As shown, the second end 522 has a convexly curved profile that

is similar to some comfortable, conventional toothbrush heads. This convex curve allows the end of the toothbrush 510 to be easily and comfortably received within the user's mouth during brushing. Additionally, the soft material used to form the stem 542 will deflect when it engages a portion of the user's mouth. As a result, the soft, flexible material of the stem 542 provides the user with additional comfort.

The body of this support member 540 includes the stem 542 that carries a support head 543 and a flexion control member 541. The support head 543 has a greater diameter/width than the stem 542 and forms a partial mushroom-like shape, as illustrated. The portion 545 of the support head 543 that overhangs the stem 542 is similar to overhanging portion 535. The overhanging portion 545 is movable relative to the base 524 and includes a lower surface 546 that is spaced from the base 524 by a distance 548. As shown, a channel 549 is formed between the lower surface 546 and the base 524. The distance 548 is less than a distance 547 that the overhanging portion 545 extends beyond the stem 542 in the direction of the first end 521. Alternatively, the distance 548 could be greater than the distance 547, as discussed above with respect to support member 530. The distance 548 allows the overhanging portion 545 to deflect toward the base 524 and provide the same cleaning benefits discussed above with respect to the first support element 530. Additionally, the support member 540 is capable of achieving 360 degrees of movement relative to its central longitudinal axis.

As shown in FIG. 10, the head 514 also includes at least one intermediate support member 560 positioned between the support members 530, 540. The total number of intermediate support members 560 can vary based on their size, the size of the base 524 and the distance between the support members 530, 540. As with the other support members 530, 540, the intermediate support member 560 includes a flexion control member 561, a flexible stem 562, and a flexible support head 563 that receives a carrier 525.

As shown in FIG. 10, the support member 560 has a substantially mushroom-like shape. A lower surface 564 of the support head 563 is spaced from the base 524 by a distance 568 that is less than its length 567 from the stem 562. Nevertheless, the distance 568 is sufficient to permit the flexible support head 563 to deflect in any direction toward the base 524. In an alternative embodiment, the length 567 can be less than the distance 568 so that the base 524 cooperates to control the total deflection of the stem 562. Due to its shape and materials, the intermediate support member 560 can deflect in any direction. The support head 563 is capable of flexing in the direction of the first end 521, the second end 522 and/or the sidewalls of the head 520. As a result, the resilient intermediate support member 560 is capable of moving in all directions to provide enhanced cleaning to the teeth of the user.

While only a few toothbrush variations are disclosed herein, the invention could be used in toothbrushes having many variations in, for example, the head, handle, and materials used. Additionally, the toothbrush could be a powered toothbrush. The head 520 can also be removably secured to the handle 512 whether it is powered or manual. Further, those skilled in the art will appreciate that there are numerous variations and permutations of the above described systems and techniques. It is to be understood that other embodiments may be utilized and structural and functional modifications may be made without departing from the scope of the present invention.

While the foregoing description and drawings represent the exemplary embodiments of the present invention, it will be understood that various additions, modifications and sub-

11

stitutions may be made therein without departing from the spirit and scope of the present invention as defined in the accompanying claims. In particular, it will be clear to those skilled in the art that the present invention may be embodied in other specific forms, structures, arrangements, proportions, sizes, and with other elements, materials, and components, without departing from the spirit or essential characteristics thereof. One skilled in the art will appreciate that the invention may be used with many modifications of structure, arrangement, proportions, sizes, materials, and components and otherwise, used in the practice of the invention, which are particularly adapted to specific environments and operative requirements without departing from the principles of the present invention. The presently disclosed embodiments are therefore to be considered in all respects as illustrative and not restrictive, the scope of the invention being defined by the appended claims, and not limited to the foregoing description or embodiments.

What is claimed is:

1. A toothbrush comprising:

a head extending along a longitudinal axis from a first end proximate a neck to a second free end distal the neck, the head comprising a base;

a cleaning, element support member comprising a stem located on the longitudinal axis extending from the base and a support head, the stem comprising a first portion and a second portion, the support head having an outer peripheral edge comprising as first portion that overhangs the second portion of the stem and a second portion that is free of an overhang relative to the first portion of the stem;

the first portion of the stem, the second portion of the outer peripheral edge of the support head, and a portion of an outer surface of the base forming a continuous surface at the second free end of the head;

a gap formed between an undersurface of the support head and the base, the support head having an overhanging portion that extends from the second portion of the stem in a cantilevered manner toward the first end of the head, the overhanging portion of the support head capable of deflecting into the gap in a direction toward said base; and

tooth cleaning elements extending from the support head of the cleaning element support member.

2. The toothbrush of claim 1 wherein the support head has a greater width than the stem.

3. The toothbrush of claim 1 wherein the continuous surface at the second free end of the head comprises a convex curve.

4. The toothbrush of claim 1 wherein the gap extends transversely the entire width of the head.

5. The toothbrush of claim 1 wherein the overhanging portion extends a first distance from the stem and the undersurface of the support head is separated from the base by a second distance via the gap, the first distance being greater than the second distance.

6. The toothbrush of claim 5 wherein the overhanging portion comprises the undersurface.

7. The toothbrush of claim 1 wherein said tooth cleaning elements are positioned on the support head so that a first axis that is substantially normal to said longitudinal axis of said head intersects said gap and a point on a top surface of the support head from which at least one of said tooth cleaning elements extends.

8. The toothbrush of claim 1 wherein the support head comprises a carrier plate formed of a hard plastic.

12

9. The toothbrush of claim 8 wherein the hard plastic comprises polypropylene.

10. The toothbrush of claim 8 wherein the tooth cleaning elements comprise bristle tufts that are anchored to the carrier plate via anchor free tufting.

11. The toothbrush of claim 1 wherein the overhanging portion terminates in a free end.

12. The toothbrush of claim 1 further comprising:
the support head having a greater width than the stem; the continuous surface at the second free end of the head comprising a convex curve;

the overhanging portion extending a first distance from the stem and the undersurface of the support head separated from the base by a second distance via the gap, the first distance being greater than the second distance; and the tooth cleaning elements positioned on the support head so that a first axis that is substantially normal to said longitudinal axis of said head intersects said gap and a point on a top surface of the cleaning element support member from which at least one of said tooth cleaning elements extends; and

the support head comprises a carrier plate formed of a hard plastic, the tooth cleaning elements comprising bristle tufts that are anchored to the carrier plate via anchor free tufting.

13. A toothbrush comprising:

a handle;
a head extending along a longitudinal axis from a proximal end connected to the handle to a free distal end, the head comprising a base;

a cleaning element support member extending from the base and comprising a stem located on the longitudinal axis and a support head having an outer peripheral edge, the stem comprising a first portion and a second portion, a first portion of the outer peripheral edge of the support head overhanging the second portion of the stem and a second portion of the outer peripheral edge of the support head free of an overhang relative to the first portion of the stem;

the first portion of the stem, the second portion of the outer peripheral edge of the support head, and a portion of an outer surface of the base forming a continuous surface at the free distal end of the head;

the support head having an overhanging portion that extends from the second portion of the stem in a cantilevered manner toward the proximal end of the head; and tooth cleaning elements extending from the support head of the cleaning element support member.

14. The toothbrush of claim 13 wherein the support head is spaced a distance from the base, the distance forming a gap between an undersurface of the overhanging portion of the support head and the base, and wherein the support head is capable of deflecting into the gap in the direction of the base.

15. The toothbrush of claim 13 wherein the overhanging portion extends a first distance from the stem and the undersurface of the support head is separated from the base by a second distance via the gap, the first distance being greater than the second distance.

16. A toothbrush comprising:
a handle;
a head extending along a longitudinal axis from a proximal end connected to the handle to a free distal end, the head comprising a base;
a cleaning element support member extending from the base and comprising a support head, the support head comprising an outer peripheral edge and an overhanging portion;

13

a portion of the outer peripheral edge of the support head and a portion of an outer surface of the base forming a continuous surface at the free distal end of the head, the continuous surface located on the longitudinal axis; a gap formed between an undersurface of the overhanging portion of the support head and the base, the overhanging portion capable of deflecting into the gap in the direction of said base, the overhanging portion of the support head extending in a cantilevered manner toward the proximal end of the head; and tooth cleaning elements extending from the support head of the cleaning element support member.

17. The toothbrush of claim 16 wherein the cleaning element support member comprises a stem extending from the base, the stem located on the longitudinal axis. 15

18. The toothbrush of claim 17 wherein the overhanging portion of the support head extends a first distance from the stem, the undersurface of the overhanging portion separated from the base by a second distance via the gap, the first distance being greater than the second distance. 20

19. The toothbrush of claim 18 wherein the support head has a greater transverse width than the stem.

20. The toothbrush of claim 17 wherein the tooth cleaning elements are positioned on the support head so that: (1) a first axis that is substantially normal to said longitudinal axis of said head intersects said gap and a point on a top surface of the support head from which at least one of said tooth cleaning elements extends; and (2) a second axis that is substantially nonparallel to said longitudinal axis of said head intersects said stem and a point on a top surface of the support head from which at least one of said tooth cleaning elements extends.

21. A toothbrush comprising:

a handle;

a head connected to said handle and extending along a longitudinal axis from a proximal end to a distal end, the head having:

a body portion;

a base member at the distal end of the head and protruding outwardly from a front surface of the body portion, the base member being substantially non-mov- 35

5

10

20

25

30

35

14

able relative to the body portion and comprising at least one outwardly extending tooth cleaning element;

a plurality of pods, each of the plurality of pods comprising at least one outwardly extending cleaning element, each of the plurality of pods movable relative to the body portion and resilient so that the at least one cleaning element of said plurality of pods is movable from an initial position and being returnable to said initial position;

a channel separating adjacent ones of the plurality of pods so that each of the plurality of pods can move independent of one another;

wherein a first portion of the base member forms a smooth continuous surface with a portion of a peripheral surface of the body portion, the smooth continuous surface located on the longitudinal axis at the distal end of the head; and

wherein the base member comprises an overhanging portion opposite the first portion that extends in cantilevered manner toward the proximal end of the head.

22. The toothbrush of claim 21 wherein the channel extends transversely.

23. The toothbrush of claim 21 wherein the body portion and the base are formed of a hard plastic material,

24. The toothbrush of claim 21 wherein each of the plurality of pods comprises a plate spaced from the body portion and to which the at least one cleaning element of said plurality of pods is mounted.

25. The toothbrush of claim 24 wherein the plate is formed of a hard plastic.

26. The toothbrush of claim 21 wherein the plurality of pods are a unitary subassembly coupled to a remaining portion of the head.

27. The toothbrush of claim 21 further comprising a second base member protruding outwardly from the front surface of the body portion, the second base being substantially non-movable relative to the body portion and comprising at least one outwardly extending tooth cleaning element, the second base member located on the longitudinal axis.
